(57) CLAIM

The ornamental design for a brush, as shown and described.

DESCRIPTION

FIG. 1 is a perspective view of a brush showing my new design.

FIG. 2 is a front elevation view thereof; a rear elevation view, right side elevation view, and left side elevation view being the same.

FIG. 3 is a top plan view thereof; and,
FIG. 4 is a bottom plan view thereof.

The broken lines show portions of the design that form no part of the claimed design.

1 Claim, 4 Drawing Sheets

FIG. 1

FIG. 4
